UNITED STATES PATENT OFFICE

HARRISON W. ROGERS, OF NEW YORK, N. Y.

ELECTRICAL RECORDING APPARATUS

Application filed December 13, 1926. Serial No. 154,580.

This invention relates to improvements in electrical sound recording and reproducing apparatus whereby the electromagnetic means is employed to influence a stylus actuated member, or be influenced thereby, especially adapting the present invention for making records of any character of sound for use in sound reproducing machines separably or in conjunction with motion picture cameras and projectors and for producing such sounds.

A further object of this invention is the provision of a polarized magnetic device in which there is practically no mechanical rebound or oscillation of the armature to produce irregular lines in forming the sound groove but which will only form the groove directly as influenced by the sound.

In the accompanying drawings:—

20 Figure 1 is a side elevation of the complete device.

Figure 2 is an end view of the magnets and associated armature, coils and stylus carrying member.

25 Figure 3 is a detail view of the stylus carrying member per se.

Figure 4 is a view of a modified form of recorder-reproducer.

The present type of pick-up is of the type 30 in which two permanent magnets 5 and 5', are supported in a swingingly mounted casing A, which latter casing is attached by set screws *t* to the fulcruming rod *a*, rotatably mounted transversely of the carrying hollow arm

35 B, which as is customary is mounted for lateral swinging movements. A rod C extends from the rod *a* and out of the arm B, carrying an adjustable counter balancing weight *c*, through the medium of which the 40 pressure of the stylus may be regulated relatively to the sound record.

The respective coils 6 and 6' are attached to the respective magnets 5 and 5', and are normally in a closed electrical circuit, while 45 resting upon the respective south poles 7—7', are the armatures 8—8'. Carried bodily by these armatures are the respective coils 11—11', which when the pick-up is in operative relation are connected in the circuit, that in 50 turn is connected to the first stage of an am-

plification circuit, the ends of the armatures extending above the respective north poles of the magnets 5—5', and terminating in spaced relation to each other, and so as to receive and support between such free ends the stylus carrying member 10, there being coacting receptacles and pintles 9 forming such support, and permitting the rocking of the stylus carrying member laterally due to the action of the phonic groove of the disc record, and so 55 that the respective armatures 8—8' will be accordingly moved to and from the respective north poles of magnets 5—5', and thus cause the desired effect to be transmitted to and through the amplifying system. 60

Inasmuch as the two coils 6—6' are connected in an independent closed electrical circuit, and the coils 11—11' are connected in the circuit that is influenced by the recorded sound waves or the waves that are to be reproduced, when the device is used as a "pick-up", it will be evident that the armatures will be continuously affected by the current influence through the coils 6—6', and that when the coils 6—6' are influenced by the impressions thereon through the sending or recording circuits, that there will be a tendency to suppress the undue oscillations of the armatures and consequently the stylus carrying member. Thus the coils 6—6' so mounted 75 70 displace the usual braking devices, such as springs or rubber tubes usually employed to counteract undue mechanical movements in the stylus carrying member. 80

From the foregoing description it will be 85 seen that as one armature 8 is attracted the stylus 12 will be moved in one direction due to the reception of the sound when the device is used as a recorder while the opposite armature 8' will act as a retarding means to prevent an undue movement of the stylus in the impelled direction, the opposite armature 90 when attracted effecting the stylus in the opposite direction and being retarded in a similar manner by the unattracted armature. 95

In Figure 4, is illustrated a modified form in a more or less diagrammatic scheme differing from that shown in Figures 1 and 2, in that the coils 6—6', are positioned slightly different, but so as to have the same influence 100

upon the north poles of the magnets, and consequently influence the various armatures 8—8'. The other form however, is preferable because of its compactness and ease of mounting, and wherein the magnets are mounted by the screws 12 and 13 carried by and to the casing A.

This "electrical pick-up" may be supported as shown in Figure 1 within an end member A, pivoted at a to the tone arm B, the stylus carrying member 10 projecting thru the bottom, as shown, to engage the record face, and an extension C, with the adjustable weight c, being provided to balance the weight of the pivoted end, said extension and weight being reached thru the aperture b in the tone arm. Additional adjustment between the swinging end and the extension C is provided by tension means t.

Mechanical damping of the member 10 by a spring S is shown in Figure 3 and may be additional to the electrical damping described.

From the foregoing description it will be appreciated that the present device can be used as a recording instrument as well as a reproducing or "electrical pick-up" for sound reproducing machines.

What I claim as new is:—

1. An electric recorder-reproducer, including two permanent magnets, two armatures, one to each magnet mounted with their free ends toward each other, a coil for each magnet, a coil carried by each armature, and a stylus carrying member suspended between the free ends of said armatures and operated thereby, whereby the coils of the armatures are to be in an uninfluenced closed electrical circuit while the other coils are located in a circuit to influence or to be influenced by the sound wave reproducing or recording.

2. A stylus recorder-reproducer, including two bi-polar permanent magnets, two coils, one coil being under the influence of one pole of each magnet, two armatures influenced respectively by the coil carrying poles of said magnets, two additional coils, one coil carried by each armature, and a stylus carrying member supported by the armatures and capable of being oscillated by the armatures.

3. A stylus recorder-reproducer, including two bi-polar permanent magnets, two coils, one coil being under the influence of one pole of each magnet, two armatures, one magnetically pivoted to the remaining terminal of said magnets, the free ends of said armatures being toward and spaced from each other, a coil carried by each armature, and a stylus carrying member supported by and between the free ends of the armatures, and through which oscillatory movement is imparted to the member.

4. A stylus recorder-reproducer, including two bi-polar permanent magnets, two coils, one to influence each permanent magnet, two

armatures pivoted, one to a pole of each magnet, the inner free ends of the armatures being spaced from each other, and a stylus carrying member pivoted between and supported by the free ends of the armatures, whereby as the armatures are simultaneously swung in opposite directions oscillatory movement is imparted to the stylus carrying member.

5. A stylus recorder-reproducer, including two bi-polar permanent magnets, two coils, one to each magnet and under the influence of one pole of one magnet, two armatures magnetically pivoted, one to each remaining pole of the magnets, the inner ends of the armatures being spaced and toward each other, two more coils, one carried by each armature, and a stylus carrying member pivoted between and supported by the free ends of the armatures, whereby as the armatures are simultaneously swung in opposite directions oscillatory movement is imparted to the member.

6. A stylus recorder-reproducer, including two bi-polar permanent magnets, two coils, one to each magnet and under the influence of one pole of its magnet, two armatures, one end of each being magnetically mounted upon its respective remaining pole of the magnets, the free ends of the armatures being toward and spaced from each other, and in attractive relation to the coil carrying ends of the first magnet, a coil carried by each armature, and a stylus carrying arm supported between and carried by the two armatures, whereby as the armatures are simultaneously moved in opposite directions the arm is oscillated.

7. A stylus recorder-reproducer, including two bi-polar permanent magnets, two coils, one attached to one pole of each magnet, two armatures, supported by two remaining poles of the two magnets and having their free ends toward and spaced from each other and in such a manner that the free end of one armature will move simultaneously with and in an opposite direction to the free end of the other armature, and a stylus carrying member operably connected to the free ends of the armatures and oscillatory by said armatures.

8. A stylus recorder-reproducer, including two bi-polar permanent magnets, two coils, one attached to one pole of each magnet, two independent armatures, each supported by one magnetic pole of each magnet, and said armatures having their free ends toward and spaced from each other and in such manner that the free ends of one armature will move in an opposite direction to the free end of the other armature, and a stylus carrying arm operably connected to the free ends of both armatures and oscillated by said armatures.

9. A stylus recorder-reproducer, including two bi-polar permanent magnets, two coils, one attached to one pole of each magnet, two independent armatures, each supported by one magnetic pole of each magnet, and said

armatures having their free ends toward and spaced from each other and in such a manner that the free ends of one armature will move in an opposite direction to the free end of the other armature, a stylus carrying member operably connected to the free ends of the armatures and oscillated by said armatures, and a damping means for the stylus carrying member.

10. A stylus recorder-reproducer, including two bi-polar permanent magnets, two coils, one attached to one pole of each magnet, two independent armatures, each one supported by one magnetic pole of each magnet, and said armatures having their free ends toward and spaced from each other and in such a manner that the free end of one armature will move in an opposite direction to the free end of the other armature, a stylus carrying arm operably connected to the free ends of both armatures and oscillated by said armatures, and a damping means for the oscillatory arm.

In testimony whereof I affix my signature.
HARRISON W. ROGERS.
